CLAMPING DEVICE FOR SLICING MACHINES

Filed May 6, 1927

Inventor:
Eugene R. FOX,
By Nielsen & Crane Artificers.

UNITED STATES PATENT OFFICE.

EUGENE R. FOX, OF SOUTHPORT, ENGLAND, ASSIGNOR TO U. S. SLICING MACHINE COMPANY, OF LA PORTE, INDIANA, A CORPORATION OF INDIANA.

CLAMPING DEVICE FOR SLICING MACHINES.

Application filed May 6, 1927, Serial No. 189,297.

This invention relates to devices known as "clamps" or "presses" for slicing machines and by means of which the meat or other substance to be sliced can be clamped in position 5 on the feed table of the machine.

Such clamps are usually characterized by one or more rows of projecting teeth, spikes or the like adapted to grip the substance to be sliced.

10 The object of this invention is to prevent the user of a slicing machine accidentally scratching his hands by the aforesaid teeth or spikes when placing the substance to be sliced on the table of the machine, and also 15 to prevent more serious accidents should the clamp accidentally slip down on the user's hand (or hands) whilst he is positioning the substance on the table.

In order to guard against such accidents, 20 in accordance with the present invention, I provide the clamp with means for protecting the hands of the user from the teeth or other gripping parts of the clamp. The means preferably takes the form of a movable guard 25 or the like which is adapted to shield the teeth or spikes when the clamp is inoperative and to uncover or expose them when the clamp is operative.

The means may be such that, when the 30 clamp is pressed upon the substance to be sliced, the pressure exerted will be sufficient to cause the teeth or spikes to be exposed so that they may grip or penetrate the substance, and when the clamp is raised and the 35 pressure removed the teeth or spikes will again be shielded by an automatic movement of the guard.

The aforesaid means will be hereinafter referred to as a "guard".

40 The guard may consist of one or more members adapted to enclose the sharp or pointed gripping parts of the clamp, and may be of substantially U-shape in cross-section, the gripping parts being accommodated between the sides of the U. The guard may be formed with a slot, or slots, or equivalent, through which the gripping parts of the clamp can project beyond the guard, when required, as a result of relative movement between the 45 guard and said parts. Preferably, the guard is guided for movement relatively to the gripping parts of the clamp and is provided with means for limiting the movement of the

guard towards its protecting or shielding position. 55

The invention is illustrated by way of example in the accompanying drawing, in which—

Fig. 1 is an elevation of a clamp of well known type equipped with a guard according 60 to this invention;

Fig. 2 is a corresponding inverted plan; and

Fig. 3 is a section on the line 3—3 of 65 Fig. 1.

Referring to the drawing, A denotes the bar of a clamp, the ends B of which are bifurcated for reception of the uprights (not shown) of the clamping device of a slicing machine. One of the ends B is fitted with a 70 handle C (shown partly broken away). Secured to the under side of the bar A is an elongated plate D, the side edges of which are downturned and are toothed throughout their length, the teeth E thus formed constituting the substance gripping parts of the clamp. 75

As shown, the clamp is equipped with a guard 10 of substantially U-shape in cross-section, the sides 10' of the guard 10 enclosing the downturned, toothed edges of the plate D. 80

The guard 10 is fitted with two upright pins 11 passing through apertures in the bar A and plate D into the hollow body of the 85 bar A (see Fig. 3). The apertures in the plate D serve as guides for the pins 11 which are formed with collars 12, springs 13 being interposed between the collars 12 and the upper inner surface of the bar A. The springs 90 13 continuously urge the collars 12, and consequently, the guard 10 therewith, downwardly, the guard being in its lowermost position when the collars 12 bear upon the plate D (as shown in Figs. 2 and 3). 95

The guard 10 is provided with slots 14 arranged in the path of the teeth E, there being one slot for each tooth.

In operation, when the clamp is lowered and pressed on to the substance which is to be clamped in position for slicing, the guard 10 first engages the substance and is displaced upwardly thereby against the action of the springs 13. The teeth E pass through the relative slots 14 and enter into engagement 100 with the substance, which is thus securely 105

clamped in position. Thereafter, when the clamp is raised clear of the substance, the springs 13 return the guard 10 to its lowermost position in which the teeth E are enclosed by the guard.

With this arrangement, should the user of the slicing machine bring his hand into contact with the under side of the clamp, or should the clamp accidentally slip down on top of his hand, while he is positioning the substance to be sliced, the guard will protect him from injury by the teeth of the clamp.

It will be obvious that, owing to the numerous forms of clamps which are in present use on slicing machines, the invention is subject to many modifications which will be within the scope of the present invention.

I claim:

1. A clamp for slicing machines having means for gripping material to be sliced, a guard for said gripping means, springs for holding said guard in position to shield said gripping means for permitting said guard to move into a position to expose said gripping means, guides for directing the movement of said guard, and stops for limiting the movement of said guard towards its shielding position.

2. A clamp for slicing machines comprising a hollow body having gripping means at one side thereof, a guard enclosing said gripping means but movable to a position adjacent said clamp in which said gripping means are exposed, a guide for said guard extending into said hollow body, a spring within said hollow body for urging said guard into its shielding position, and a stop within said hollow body for limiting the movement of said guide toward its shielding position.

3. A clamp for slicing machines comprising a bar having teeth thereon, a channel-shaped guard embracing one side of said bar and enclosing said teeth, said guard having openings therethrough to permit said teeth to project therefrom when said guard is moved toward said bar, guides secured to said guard and extending into said bar, springs for resiliently urging said guard outwardly away from said bar, and stops on said guides for limiting the outward movement of said guard.

4. A work holder for slicing machines comprising a work support, a clamp disposed above and adjustable toward said work sup-

port, a work engaging portion carried by said clamp, and a guard for shielding said work engaging portion held in guarding relation therewith when said clamp is in inoperative position, said guard being movable to expose said work engaging portion when said clamp is in operative clamping position.

5. A work holder for slicing machines comprising a work support, a clamp disposed above and adjustable toward said work support, a work engaging portion carried by said clamp, and a guard for shielding said work engaging portion held in guarding relation therewith when said clamp is in inoperative position, said guard being movable under pressure to expose said work engaging portion when said clamp is in operative clamping position.

6. A work holder for slicing machines comprising a work support, a clamp disposed above and adjustable toward and away from said work support, a penetrating work engaging portion carried by said clamp, and a guard for shielding said work penetrating portion held in guarding relation therewith when said clamp is in inoperative position, said guard being movable under pressure to expose said penetrating work engaging portion when said clamp is in operative clamping position.

7. A work holder for slicing machine comprising a work support, a clamp adjustable toward and from said work support, a work engaging portion carried by said clamp, a guard for shielding said work engaging portion, and resilient means normally holding said guard in shielding position, said means being yieldable under pressure to expose said work engaging portion.

8. A work holder for slicing machines comprising a work support, a clamp adjustable toward and from said work support, teeth carried by said clamp, a guard for shielding said teeth, said guard having openings therethrough which said teeth may project, and springs normally acting to hold said guard in spaced relation with said clamp to enclose said teeth but permitting compression of said guard toward said clamp to cause said teeth to project through said openings.

In testimony whereof I have signed my name to this specification on this 14th day of April A. D. 1927.

EUGENE R. FOX. [L. S.]
